UNITED STATES PATENT OFFICE.

WILLIAM RENNYSON AND HUGH BURGESS, OF NORRISTOWN,
PENNSYLVANIA.

GAS APPARATUS.

SPECIFICATION forming part of Letters Patent No. 393,662, dated November 27, 1888.

Application filed January 11, 1888. Serial No. 260,459. (No model.)

To all whom it may concern:

Be it known that we, WILLIAM RENNYSON and HUGH BURGESS, the latter a subject of the Queen of Great Britain and the former a citizen of the United States, both residing at 5 Norristown, in the county of Montgomery and State of Pennsylvania, have invented certain new and useful Improvements in Gas Apparatus, of which the following is a specification, 10 reference being had therein to the accompanying drawing.

This invention relates to certain improvements in the manufacture of gas from the fluid hydrocarbons, such as petroleum and the like; 15 and it has for its objects to provide a fixed gas for illumination and fuel that will not condense and form deposits in the pipes and other fixtures, as more fully hereinafter set forth.

In the manufacture of gas from petroleum 20 and other fluid hydrocarbons the great desideratum is to convert the hydrocarbon into a non-condensable or fixed gas which will preserve its gaseous form when cool, and which will not assume a liquid form again under ordinary temperatures. Heretofore it has been 25 impossible to accomplish this result with the apparatus in ordinary use, owing to the imperfect manner of heating the same, so as to secure the proper temperature and maintain 30 it uniformly during the process of generating the gas.

Our invention is designed to obviate these objections; and to this end it consists in so constructing the retorts or generating-chambers that they may be heated from within, 35 as well as from the outside, by a tubular core, or so that the heat may be stored within said retorts or chambers and conducted or radiated with uniformity through the same to insure the perfect decomposition of the fluid hydrocarbon and produce a practically fixed 40 gas for lighting and heating, as more fully hereinafter set forth.

The accompanying drawing, forming part of 45 this specification, represents a longitudinal vertical sectional view of the apparatus we employ in practicing our invention.

Referring to the drawing, the letter A indicates a furnace constructed of masonry or other

suitable material; B, the fire-chamber thereof, 50 and C the ash-pit of the same.

D indicates a retort or series of retorts, which may be either round, oval, or polygonal in cross section.

E indicates a core located within the retort 55 and supported by means of a series of pins or projections, F, which serve the additional purpose of radiating, conducting, and distributing the heat and breaking up the fluid hydrocarbon into gaseous form, so as to thoroughly 60 present every portion of it to the action of the heat and insure its conversion into a fixed gas. The said core is hollow and extends through the retort or series of retorts from the combustion-chamber of the furnace or other means of 65 creating sufficient draft to the smoke-stack or chimney, as shown in the drawing, so as to heat the retort or retorts from the inside as well as the outside.

The letter G indicates a pipe leading into 70 one end of the retort, or lower retort when a series of such are employed. The said pipe is provided with a funnel, injector, or any other well-known means of introducing the hydrocarbon.

H indicates a similar pipe for the introduction of water or steam with the hydrocarbon. The said pipe, however, may be omitted and a combined steam and oil injector substituted 75 therefor.

The operation of our invention is as follows: The furnace being supplied with fuel and heated to the proper temperature, the hydrocarbon and water or steam are introduced in proper quantities and decomposed in the retort or retorts, producing a permanent gas, 85 which passes out through the pipe I to the gas-holder or other place of storage or use. The products of combustion pass up and around the retorts, and in the case a hollow core is 90 employed through the same heating the retort or retorts from the inside as well as the outside.

Having thus fully described our invention, what we claim, and desire to secure by Letters 95 Patent, is—

1. The combination, in a gas-generator, of a series of connected retorts and a series of

hollow cores extending through the same and connected with the combustion chamber and exit-flue of the furnace in which the retorts are located, substantially as and for the purposes specified.

5. 2. The combination, in a gas-generator, of a series of connected retorts and connected hollow cores supported concentrically within the retorts by radial pins or supports and communicating with the combustion chamber and

exit-flue of the furnace in which the retorts are located, substantially as and for the purposes specified.

In testimony whereof we affix our signatures in presence of two witnesses.

WILLIAM RENNYSON.

HUGH BURGESS.

Witnesses:

CHAS. B. BALLARD,

RICHARD RIGHTER.
